SHEET CARRIER CONTROL MECHANISM

Application filed March 29, 1930. Serial No. 440,012.

This invention relates to a carrier control mechanism for machines in which a travelling carrier is employed to guide or carry a sheet of material into engagement with rolls or cylinders over which said sheet must pass during the process of manufacture.

In a paper making machine, for example, continuously travelling rope carriers are employed to carry the paper sheet through the 10 various press and drier sections. Although these rope carriers are needed principally for starting purposes, or when a break occurs in the paper, they are invariably arranged to travel continuously during operation of the 15 paper making machine. The wear incident to continuous travelling of the carrier ropes in contact with the press or drier rolls is the cause of considerable operating and other losses due to the necessity of frequently stopping the machine to repair or replace the 20 broken, damaged or worn out ropes.

The present invention has been designed to eliminate this difficulty and consists in the 25 provision of means whereby the travelling motion of the rope carriers in paper making and analogous machines is automatically arrested when the ropes have completed their function of guiding the sheet of paper or other material into engagement with the 30 various rolls over which the sheet is intended to travel. Means are also provided to enable the travel of the carrier ropes to be arrested at the will of the machine operator.

In the present instance, the invention will 35 be described with reference to its application to the third press section of a newsprint paper making machine. It will be understood however that the invention, as hereinafter described, or with slight modifications, may be 40 applied to the first or second press sections; to the drier section or to any other section of a newsprint or other paper making machine, as well as to other types of machines in which 45 a carrier is employed to guide a sheet of material into engagement with a series of rolls or cylinders.

Proceeding now to a more detailed discussion of the invention, reference will be had to the accompanying drawings, wherein 50 Figure 1 is a fragmentary side elevation of

the third press section of a newsprint paper making machine, having our invention applied thereto.

Figure 2 is a sectional view taken on the line 2—2 of Figure 1, certain parts being 55 omitted for the sake of clearness.

Figure 3 is an enlarged fragmentary view, partly in side elevation and partly in vertical section, of an automatic control mechanism employed for arresting the travelling 60 movement of the carrier ropes when the paper guiding operation is completed.

Figure 4 is a plan view showing the manner in which the control mechanism illustrated in Figure 3 is operatively connected to one of 65 the felt rolls of a paper making machine.

Figure 5 is a fragmentary side elevation of the arrangement shown in Figure 4 with certain parts omitted for the sake of clearness.

Figures 6, 7 and 8 are side, plan and end views, respectively, of a suction head forming part of the automatic control mechanism disclosed in Figure 3.

In accordance with this invention, a felt roll 5 of the dryer section is equipped with a pulley 6. This pulley, by means of a belt 7, drives a pulley 8 on the shaft 9. A friction gear 10, fixed to the shaft 9, engages a complementary friction gear 11 fixed to a shaft 12. Drive sheaves 13 and 14 are keyed to shaft 12 and serve to drive the carrier ropes 15 and 16 which travel in the direction indicated by the applied arrows in Figure 1. The rope 15 travels from the drive sheave 13 75 beneath a guide sheave 17 and thence upwardly to a felt roll 18 positioned between the third press section A and the second press section B. From felt roll 18 the rope 15 travels around the felt rolls 19 and 20 of the 80 third press section. After leaving roll 20, the rope 15 travels over idle pulleys 21, mounted at one end of the upper press roll 22, and from thence over felt roll 23, to the idler pulleys 24 mounted at one end of the 85 drying roll 25. After leaving the idler pulleys 24, the rope 15 passes beneath a tensioning pulley 26 back to the drive sheave 13. The companion rope 16 passes from the guide 90 sheave 17 to a pulley 28 located at the top of 95 the drying roll 25. After leaving the idler pulleys 24, the rope 15 passes beneath a tensioning pulley 26 back to the drive sheave 13. The companion rope 16 passes from the guide 100 sheave 17 to a pulley 28 located at the top of

the third press section. From pulley 28, the rope 16 passes downwardly around an intermediate pulley 29 to a lower pulley 30. After passing beneath said pulley 30, the 5 rope 16 follows the same path as rope 15 to the idler pulleys 24. From the pulleys 24, the rope 16 passes beneath a tensioning pulley 31 back to the drive sheave 14.

The paper coming from the second press 10 section B, as indicated at K, is caught between the travelling ropes 15 and 16 and is thereby carried through the third press section until it reaches the drying roll 25. From this point on, the paper is taken care of by 15 the driers in the usual manner.

After the ropes 15 and 16 have performed their function of guiding the paper through the third press section, the travelling movement of the ropes is discontinued by separating the friction drive gears 10 and 11. Provision for separating these gears 10 and 11 20 both automatically and manually is made in the following manner.

As shown to advantage in Figures 3 to 5 25 inclusive, shaft 9 is journalled in stationary bearings 34 carried by a pair of brackets 35 suspended from the framing A' of the third press section A. Shaft 12 is journalled in bearings 36 carried by a vertically slideable 30 plate 37. This plate 37 slides in suitable guides 38 on the brackets 35. A lever 39 is intermediately pivoted at 40 to one of the brackets 35. One end of this lever is attached to the plate 37, while the other end 35 is attached, by a vertical stem 41, to the diaphragm 42 of a suitably supported liquid reservoir 43, which communicates with a vacuum chamber 44 equipped with a liquid gauge 45. The top of the vacuum chamber 40 is connected by suitable fittings to pipes 46, 47 and 48. Pipe 46 leads to a water supply (not shown) and is equipped with a shut-off valve 49. Pipe 47 leads to a vacuum pump (not shown) and is equipped with a control 45 valve 50. Pipe 48 connects vacuum chamber 44 to a suction head 51 and is equipped with a branch 52 which may be opened to the atmosphere through a valve 53. The suction head 51 is provided with a vacuum chamber 54 which communicates with the main vacuum chamber 44 via the pipe 48. One side 50 of vacuum chamber 54 is formed by a removable face plate 55, provided with openings 56 and held in place by bolts 57. Between the branch connection 52 and the main vacuum chamber 44, pipe 48 is equipped with an air filter or dust collector 58. Said filter or collector 58 includes a fitting 59 having an inlet 60 and an outlet 61 separated by a partition 62 having an opening formed therein. The inlet 60 communicates with a tubular dust receiver 63 which surrounds a tubular screen or strainer 64 having its upper end supported in the opening of partition 62 and 55 communicating with outlet 61.

The complete operation of the invention will now be described with reference to the guiding or carrying of the paper sheet from the second press section B through the third press section A. In accordance with present 70 practice, a narrow strip or ribbon of the paper is initially engaged between the ropes 15 and 16 but, as the guiding of the paper progresses, this ribbon or strip is gradually widened to the full width of the paper web. 75 At the beginning of the paper guiding operation, the suction head 51, which is positioned as shown to advantage in Figures 1 and 2, is open to the atmosphere. This permits atmospheric pressure to act through the pipe 48 80 and to depress the water level in vacuum chamber 44. Upward pressure is thus exerted on diaphragm 42 and stem 41 to move lever 39 in the direction necessary to lower the friction gear 11 into engagement with the driving gear 10, whereby motion is imparted to the carrier ropes 15 and 16. As the guiding of the paper through the third press section is completed and the paper widens to its full width, the openings 56 of suction head 51 90 are sealed by contact with the paper web passing thereover. This sealing of the suction head disrupts communication between the atmosphere and the vacuum chamber 44 so that a vacuum is established in said chamber 44 95 through the agency of the vacuum pipe 47. The pull of the vacuum thus created in chamber 44 causes the diaphragm 42 to move downwardly with the result that the stem 41 and lever 39 are actuated in a direction to lift the plate 37, thus separating friction gears 10 and 11 and arresting the travelling movement 100 of ropes 15 and 16.

Any dust that may be created by contact of the paper sheet or web with the suction head 51 is prevented by the filter or dust collector 58 from entering and clogging the valve 50 and vacuum pipe 47.

Should the functioning of the suction head 51 be temporarily interfered with by clogging of the openings 56, the valve 53, in branch pipe 52, may be opened to permit atmospheric pressure to act on the water contained in vacuum chamber 44. This enables the ropes 15 and 16 to be set in operation whenever a 115 break occurs in the paper, even though the suction head 41 is not functioning properly. Any suitable means, such as a valve inserted in the pipe 48, may be provided to enable the stopping of the ropes 15 and 16 to be controlled at the will of the machine operator. The closure of such a valve manually would have the same effect as the sealing of the openings 56 in the suction head 51.

While in the foregoing we have disclosed 125 what we now consider to be the preferred embodiment of our invention, it will be understood that the principles involved may be reduced to practice in various other ways. For example, various means, other than the spe- 130

cific means herein described, may be found suitable for controlling engagement and disengagement of the friction drive gears 10 and 11. Likewise, these friction drive gears 10 and 11 may be supplanted by other suitable devices for establishing and disrupting a drive connection between the carrier ropes and the paper making machine or other source of power. All such modifications as fall within the scope of the appended claims 10 are considered within the purview of our invention.

Having thus described our invention, what we claim is:—

15 1. The combination with a series of rolls and a travelling carrier functioning to guide a sheet of material into engagement with said rolls, of means co-acting with said sheet to cause travelling motion of the carrier to cease at a predetermined time.

20 2. The combination with a machine, including a series of rolls and a travelling carrier for guiding a sheet of material into engagement with said rolls, of means functioning automatically to establish and disrupt a drive connection between said carrier and a driving means therefor.

25 3. The combination with a series of rolls and a carrier for guiding a sheet of material 30 into engagement with said rolls of means functioning automatically, in co-operation with said sheet, to establish or disrupt a drive connection between said carrier and a source of power dependent upon operating conditions.

35 4. The combination with a carrier for guiding a sheet of material into engagement with a series of rolls, of power operated means for establishing and disrupting a drive 40 connection between said carrier and a carrier driving member.

45 5. The combination with a carrier for guiding a sheet of material into engagement with a series of rolls of a drive member, a drive connection between said member and carrier, and means for automatically disrupting said drive connection when the guiding of the paper is completed.

50 6. The combination with a carrier for conveying a sheet of material into engagement with a series of rolls, of a drive member, and means for automatically establishing and disrupting a drive connection between said member and carrier, said means including provision for manual control thereof.

55 7. The combination with a paper machine equipped with a power driven carrier for leading the paper sheet through the machine when starting up or following breakage of the sheet of an automatic carrier control mechanism functioning to effect actuation of the carrier when conditions render it necessary to lead the sheet through the machine and to discontinue further operation of the

carrier when the aforesaid leading of the sheet is completed.

8. The combination with a series of rolls and a travelling carrier for guiding a sheet of material into engagement with said rolls of a fluid pressure responsive device controlling the functioning of said carrier.

70 9. The combination with a series of rolls and a travelling carrier for guiding a sheet of material into engagement with said rolls of means, including a fluid pressure responsive device, for automatically establishing and disrupting a drive connection between the carrier and a driving means therefor.

75 10. The combination with a series of rolls and a travelling carrier for guiding a sheet of material into engagement with said rolls of means for automatically controlling the starting and stopping of said carrier, said means including a pressure responsive device 80 for establishing and disrupting a drive connection between the carrier and a source of power and a control member serving, in co-operation with said sheet, to control the actuation of the pressure responsive device.

90 11. An automatic sheet carrier control mechanism for paper making and analogous machines comprising a differential pressure device for establishing and disrupting a drive connection between the carrier and a drive member therefor, said device including a source of suction and a suction head connected therewith, said head having openings to the atmosphere positioned to be sealed by the sheet only when the full width of the 95 sheet is passing through the machine and means responsive to the sealing and unsealing of said openings for controlling the action of said device.

100 12. An automatic sheet carrier control mechanism of the character described comprising a differential pressure device for establishing and disrupting a drive connection between the carrier and a drive mechanism, said device including a vacuum chamber and means for establishing and disrupting communication between said chamber and the atmosphere to control the actuation of said device.

105 13. A sheet carrier control mechanism of the character described comprising a holder containing a column of liquid, means responsive to the normal head pressure of the liquid for establishing a drive connection between the carrier and a drive mechanism therefor, and means for creating a suction effect in a portion of the holder to reduce the effective 110 head pressure of the liquid and thereby disrupt said drive connection.

115 14. A sheet carrier control mechanism of the class described comprising a pressure chamber, means for varying the pressure conditions within said chamber and means responsive to the pressure variations within said chamber for establishing and disrupt- 120

130

ing a drive connection between the carrier and a source of power.

15. An automatic sheet carrier control mechanism for paper making and analogous machines comprising a drive gear, a driven gear, carrier propelling means actuated from the driven gear, one of said gears being movable into and out of engagement with the other, a pressure responsive device for moving said movable gear and means for controlling the action of said device.

16. The combination with a carrier for guiding a sheet of material into engagement with a series of rolls of a carrier control mechanism including a drive gear, a driven gear, carrier propelling means actuated from the driven gear and means, including said sheet, for automatically effecting engagement and disengagement of said gears.

17. In witness whereof, we have hereunto set our hands.

WILLIAM N. KARLS.
WILLIAM BOUCHER.
